UNITED STATES PATENT OFFICE.

CHARLES B. EHNBORN, OF GLEN ELLYN, ILLINOIS, ASSIGNOR TO THOMAS CUSACK COMPANY, OF CHICAGO, ILLINOIS, A CORPORATION OF NEW JERSEY.

ILLUMINATED SIGN AND LETTER THEREFOR.

Application filed April 24, 1924. Serial No. 708,618.

This invention relates to an improvement in signs and consists of the matters herein-after described and more particularly pointed out in the appended claims.

- 5 The object of the invention is to provide a sign and sign letter or character which are cheap and economical of construction, which are readily and easily kept clean and which provide a brilliant and bold effect both as 60
10 a day sign and night sign. Another object of the invention is to provide a sign of the kind in which the letters or characters may be easily and quickly interchanged or rearranged. 65
15 The several advantages of the novel sign and sign letter will appear more fully as I proceed with my specification.

In the drawings:—

- Fig. 1 is a view in front elevation of an 20 illuminated sign embodying my invention.

Fig. 2 is a vertical section through the same on an enlarged scale, as taken on the line 2—2 of Fig. 1.

- Fig. 3 is a view in rear elevation of one of 25 the letter or character members forming a part of my invention.

- Fig. 4 is a view in front elevation of a modified form of letter or character member forming a part of my invention.

- 30 Referring, now, in detail to that embodiment of the invention illustrated in the accompanying drawings: 5 indicates the casing or body of the sign and 6—6 indicates letter or character members associated therewith.

- 35 The casing 5 is made of sheet metal in the form of an open front box which is of a height greater than its depth and of a length which will accommodate the desired number of letter members to be used therewith.

- 40 The casing has a rear wall 7, end walls 8—8, top and bottom walls 9—10 respectively and a front wall 12 in which an elongated opening 13 is provided for the letter members. The parts of the front wall 12 defining the edges of the opening 13 are formed on their rear faces with inturned flanges 14 which stiffen said wall and give it the appearance of thickness.

- 45 Within the casing is a vertically convex reflector plate 15 which extends from the top to the bottom wall of the casing, being fixed in that position in any suitable manner. The reflector plate extends the full 50 length of the casing and is preferably paint-

ed white so as to present a bright white reflecting back-ground for the letter members, presently to be described.

Spaced a suitable distance from the top and bottom edges of the opening 13 and just 60 back of the plane of the defining flange 14 are two longitudinally extending rods 16—16 of a comparatively small diameter. Said rods are secured at their ends to the front wall parts 12—12 beyond the side edges of 65 the opening 13 in any suitable manner, and are supported at points between their ends by braces 17 which braces include rearwardly extending legs 18. The legs 18 have a hooked connection with flange strips 19—19 70 on the reflector plate.

Mounted on the top and bottom walls of the casing between the reflector plate 15 and the front wall of the casing are brackets 20—20 carrying electric lamp sockets 21—21 75 for the lamps 22, said lamps being so positioned as to be concealed from view through the opening 13.

The letter or character members 6 are adapted to be supported in the opening 13 80 in the plane of the flange 14. Each letter member comprises sheet metal strips 23—23 which are separated from each other to provide a space 24 between them. As shown in Figs. 1, 2 and 3 said strips are made of channel cross-section with their flanges directed toward the reflector plate and the strips of each letter are rigidly connected together in spaced relation by small rods 25—25 85 which are of such diameter as to be substantially invisible where they cross the spaces 24.

90 Fixed in a suitable manner to the rear face of each letter member are downwardly facing hooks 26 which are adapted to have 95 a hooked engagement upon the rods 16—16 as shown in Fig. 2. When said hooks are engaged upon said rods, they hold the letter members against swaying or other movement under wind pressure but permit the 100 shifting of the letter members longitudinally on said rods to facilitate the proper spacing of said letter members in a sign casing. Preferably the outer faces of the strips forming the letter members 6 are 105 painted a color (such as black) which will present a sharp contrast to the back-ground provided by the reflector 15. As will be noticed from Fig. 1, the supporting rods 16—16 are so arranged with respect to the 110

opening 13 and the hooks 26 are so arranged on the letter members, as to provide an equal spacing between the top and bottom strips of said letter members and the top and bottom flanges 14 of the front wall 12 defining the opening 13.

In Fig. 4 is shown a modified form of sign letter wherein the strips 23^a—23^a forming said letter member are of a double bevel cross-section instead of a channel cross-section as before described.

When a group of the letter members are supported in position in the opening 13 of a sign casing as before described, and the lamps 22 are illuminated, an odd and attractive appearance is created. The light reflected from the back-ground through the fully open letter members imparts an appearance of white or opalescent glass letters clearly defined by black out-lines upon a white back-ground. When the lamps are thus illuminated the supporting rods 16 and the wires 25—25 which connect the parts of the letter member strips together are practically invisible so that their presence in no manner detracts from the appearance of the sign.

The letter members are indeed light in weight when compared with raised glass letter plate for signs and are therefore much easier and cheaper to make and to keep clean. Furthermore the letter members may be more easily changed or shifted about than the heavy glass letter plates before referred to and will not prove so dangerous if dropped during the handling they receive when making changes in the matter to be depicted on said signs. Should snow or rain blow into the sign through the opening 13, the water therefrom will drain through suitable holes provided therefor in the bot-

tom wall of the casing between the front wall and reflector.

While in describing my invention, I have referred to certain details of mechanical construction and arrangement of parts, I do not wish to be limited thereto except as may be pointed out in the appended claims.

I claim as my invention,

1. An illuminated sign comprising in combination, an open front casing having a light reflecting back-ground, vertically spaced rods extending longitudinally of the open front of the casing, letter members removably supported and longitudinally shiftable on said rods, each letter member including spaced strips defining the out-line of a letter in contrast to said light reflecting back-ground, and concealed means in the casing for illuminating said light reflecting back-ground.

2. An illuminated sign comprising in combination, an open front casing having a light reflecting back-ground, vertically spaced rods extending longitudinally of the open front of the casing and secured at their ends to said casing, brace members for said rods engaged with and extending forwardly from said light reflecting back-ground, letter members having hooks on their rear sides adapted for a removable hooked engagement with said rods, each letter member including spaced strips defining the out-line of a letter in contrast to said light reflecting back-ground, and means concealed back of the front wall parts defining the top and bottom edges of said opening for illuminating the said light reflecting back-ground.

In testimony that I claim the foregoing as my invention, I affix my signature this 4th day of April, 1924.

CHARLES B. EHNBORN.
